UNITED STATES PATENT OFFICE.

WILLIAM BELL CHAMBERS, OF NEWARK, OHIO.

BOTTLE-STOPPER.

SPECIFICATION forming part of Letters Patent No. 400,436, dated April 2, 1889.

Application filed December 23, 1888. Serial No. 294,613. (No model.)

To all whom it may concern:

Be it known that I, WILLIAM BELL CHAMBERS, a citizen of the United States, residing at Newark, in the county of Licking and State 5 of Ohio, have invented new and useful Improvements in Bottle-Stoppers, of which the following is a specification.

My invention relates to improvements in bottle-stoppers; and it consists in a certain 10 novel construction and combination of devices, fully described hereinafter in connection with the accompanying drawings, and specifically pointed out in the appended claims.

15 In the drawings, Figure 1 is a perspective view of the stopper embodying my invention applied in the operative position to the neck of a bottle. Fig. 2 is a vertical central sectional view of the same. Fig. 3 is a detail 20 view of the ring detached from the bottle.

Referring by letter to the drawings, A designates the neck of an ordinary bottle, around which, just below the shoulder *a* thereon, is arranged the ring B, the said ring being provided 25 at diametrically-opposite points with the laterally-extending trunnions *b b*. This ring is preferably formed as shown in the drawings—namely, of the two semicircular sections B' B', of wire, the ends of which are bent 30 outward and arranged close together to form the trunnions *b*. The yoke C extends over the mouth of the bottle, and its arms *c c* (which pass down on opposite sides of the neck of the bottle) are provided at their lower ends 35 with bearings *c' c'*, in which fit the trunnions *b b*, whereby the yoke is pivoted to the neck of the bottle. A milled cap, D, fits over the mouth of the bottle, (its depending flange *d* fitting closely around the sides of the same,) 40 and a vertical threaded stud, E, which is permanently secured to the center of the cap, engages a central threaded aperture, C', in the yoke.

A ground-glass disk, E', is fitted in the cap 45 D and bears on the mouth of the bottle when the cap is screwed down in place to form an air-tight joint, and a rubber cushion, F, is arranged between the glass disk and the upper side of the cap, which is compressed when 50 the cap is screwed down, thereby insuring an

even pressure on the glass disk. A metallic disk, G, is interposed between the cushions and the glass disk to prevent friction between the same when the cap is screwed down, and a collar, *g*, is secured in the cap below the 55 glass disk to hold the latter in position.

I am aware that swinging yokes have heretofore been used in connection with bottles and in combination with stoppers provided with threaded studs; but it will be observed 60 that in the improved device the yoke is revolute on the neck of the bottle, owing to the peculiar connection thereto, and therefore after the cap has been screwed down until the glass disk is in contact with the mouth 65 of the bottle the yoke is revolved, thereby clamping the cap down more firmly than is possible by simply rotating the cap, owing to the friction between the ground glass and the bottle; also, in removing the stopper it is im- 70 possible to turn the cap until it has been loosened by first revolving the yoke.

Having thus described the invention, I claim—

1. In a bottle-stopper, the combination of 75 the revolute yoke C, connected to a ring on the neck of the bottle, the cap fitting over the mouth of the bottle and provided with a vertical threaded stud engaging a central tapped aperture in the yoke, and the ground-glass 80 disk E', secured loosely in the cap and adapted to bear on the mouth of the bottle, whereby the yoke may be rotated to raise or lower the cap without rotating the cap or the disk and the disk may be pressed against and removed 85 from the mouth of the jar, substantially as specified.

2. In a stopper, the combination, with a 90 revolute yoke connected to the neck of the bottle, of the cap provided with a threaded stud engaging a threaded aperture in the yoke, the glass disk arranged in the cap and bearing on the mouth of the bottle, the compressible cushion interposed between the said disk and the upper side of the cap, and the 95 collar arranged below the disk to hold it in place, substantially as specified.

3. In a stopper, the combination, with a 100 revolute yoke connected to the neck of a bottle, of the cap provided with a vertical

threaded stud engaging a threaded aperture in the yoke, the glass disk arranged in the cap and bearing on the mouth of the bottle, the compressible cushion between the glass disk and the top of the cap, and the metallic disk interposed between the glass disk and the cushion, substantially as described.

In testimony that I claim the foregoing as my own I have hereto affixed my signature in presence of two witnesses.

WILLIAM BELL CHAMBERS.
